UNITED STATES PATENT OFFICE.

SAMUEL HERMANN, OF CINCINNATI, OHIO.

COLLAPSIBLE STEREOSCOPE.

SPECIFICATION forming part of Letters Patent No. 774,245, dated November 8, 1904.

Application filed December 4, 1902. Serial No. 133,807. (No model.)

To all whom it may concern:

Be it known that I, SAMUEL HERMANN, a citizen of the United States of America, and a resident of Cincinnati, county of Hamilton, 5 State of Ohio, have invented certain new and useful Improvements in Collapsible Stereoscopes, of which the following is a specification.

The object of my invention is a stereoscope which may when not in use be folded 10 up so as to occupy comparatively little space and which may be quickly opened out and braced open in position for use.

In the accompanying drawings an illustration is given of a stereoscope embodying my 15 invention.

Figure 1 is a side elevation of my stereoscope in position for use. Fig. 2 is an end elevation of the same, the dotted lines showing the closed position of one of the hoods. 20 Fig. 3 is a plan view of the same. Fig. 4 is a detail view of a modified form of the hood.

Referring to the parts, the frame of the stereoscope embodying my invention consists of two plates A and B, hinged together so as 25 to be capable of a rotation from a position lying flat together to a position at ninety degrees apart. In this position they may be braced apart by a brace-arm b, pivoted to plate B, engaging a stop or ridge a upon plate A.

Plate A has struck down from it three 30 straps a', forming a way for a sliding arm C, which at its forward end has a hinged support c' for holding the stereoscopic picture M. To one of the straps a' is secured a spring a'', 35 which presses upward against arm C to hold it in any desired position. Plate B supports lenses D D' and has upon its front two dividing-strips b' and b'', which divide the angle of vision, plate A having perforations a'' and a'', 40 through which the strips b' and b'' project when the plate B is folded down upon plate A by the release of brace-arm b.

Upon the ends of plate B are hinged hoods b' and b'' in positions such that they may be 45 swung down to protect the lenses when the parts are folded together, as shown in dotted lines in Fig. 2 and Fig. 3. In Fig. 4 is illustrated a modified form of hood which consists of three parts b', b'', and b'', telescoped together, so that in use they may be spread

apart, as shown in Fig. 4, and when not in use may be pushed together, so as to occupy little space.

Plate A has upon its under side at the rear end a downward-projecting bracket a'', to 55 which is pivoted a handle E, so as to be capable of rotation upward and forward against the under side of plate A. The upper ends e of the handle are cam-shaped, as shown in Fig. 1, dotted lines, so that when the arm is 60 swung down to its vertical position the cam contacts bracket a'' to hold the arm firmly in this vertical position.

Arm E is made in the shape of a hollow frame, between the sides of which a pin E' is 65 supported. Upon pin E' is a leg F, which has an elongated slot f in its side to engage the pin, so that the leg may project forward, as shown in Fig. 1, to act as a support, so that the frame of the stereoscope will stand up- 70 right without other support and that when it is desired to fold up the device arm F may be pushed backward and upward so as to fit within frame E, as shown in Fig. 2 and Fig. 5.

It is seen that when it is desired to ship a 75 stereoscope of my invention it may be folded into a small space by turning picture-support c' down upon its arm C, pushing arm C inward so as lie beneath plate A, turning plates B and arm E downward and upward so as to 80 lie in planes substantially together to the plate A, and by turning the hoods b' and b'' down over the lenses, all as illustrated in Fig. 5.

What I claim is--

1. A frame of a stereoscope consisting of 85 two plates hinged together, so as to be capable of a rotation from a position lying flat upon each other to a position at substantially right angles thereto, one plate supporting the stereoscopic lenses, and a dividing-strip 90 between them, the other plate having a support for stereoscopic pictures, and a perforation therein for the reception of the dividing-strip of the former plate when in a flat position, and an arm hinged to the latter plate to 95 be capable of a rotation from a position flat upon it, downward at an angle thereto to form a handle, substantially as shown and described.
2. A frame for a stereoscope consisting of 100

two plates hinged together so as to lie flat upon each other, or, to stand at right angles thereto, means for bracing them apart, one of the said plates supporting stereoscopic lenses, 5 the other having a picture-support, a handle hinged to the under side of the latter plate, so as to be capable of a rotation from a position parallel to the same, down at an angle thereto, and a leg coupled to said handle, so 10 as to be capable of being projected forward to form the support for holding the frame in an upright position and to be carried in a position flat against the handle, substantially as shown and described.

15 3. A frame for a stereoscope consisting of two plates hinged together, so as to be capable of a position flat upon each other, or one at substantially right angles to each other, means for bracing them apart, one of said 20 plates supporting stereoscopic lenses, collapsible hoods supported by the plate adjacent to the lenses, a sliding arm upon the second plate for supporting stereoscopic pictures, a handle pivoted to the under side of the sec-

ond plate so as to be capable of a rotation 25 from a position parallel to the plate to a position at right angles thereto, a leg coupled to said handle, so as to be capable of being projected forward to form a support for holding the frame in an upright position, or of being 30 folded flat against the handle, substantially as shown and described.

4. In a stereoscope the frame-piece, a lens-holder hinged upon one end thereof and adapted either to stand at right angles to the frame-piece or to lie flat thereon, an extensible picture-holder sliding in ways in the frame-piece, a handle hinged to the under side of the frame-piece and capable of moving through a right angle so as either to lie against the under 35 piece of the frame, or extend at right angles thereto, an extension-arm secured to said handle to serve as a standing support for the frame, substantially as shown and described.

SAMUEL HERMANN.
